United States Patent Office

Des. 231,662
Patented May 14, 1974

231,662

WATCH

Joseph Fusillo, Jr., 2393 Union Blvd.,
Islip, N.Y. 11751

Filed May 12, 1971, Ser. No. 142,841

Term of patent 14 years

Int. Cl. D10—02

U.S. Cl. D42—1 B

The figure is a plan view of a watch showing my new design wherein the essential feature resides in the particular indicia and arrangement thereof, as shown.

I claim:

The ornamental design for a watch, substantially as shown and described.
